COMPRESSED AIR SWITCH WITH DELAYED
BREAK CONNECTOR

André Latour, Grenoble, France

Application January 23, 1947, Serial No. 723,728
In France March 8, 1945Section 1, Public Law 690, August 8, 1946
Patent expires March 8, 1965

6 Claims. (Cl. 200—148)

1

The present invention relates to a circuit breaker, and more particularly to a circuit breaker of the gas blast type.

In circuit breakers of the kind described it has been suggested to connect temporarily a resistor across the main contacts, the resistor forming part of an electric circuit containing two electrodes separated by a gap. However, the known circuit breakers of this kind have the drawback that the resistor is connected in shunt to the main contacts either too late or too early for an efficient extinction of the arc between the main contacts.

It is an object of the present invention to overcome this drawback.

It is another object of the present invention to start and extinguish an arc between the electrodes forming the gap with a time delay being independent of the main flow of the gas blast.

The present invention consists in a circuit breaker of the gas blast type comprising in combination, a first contact, a second contact arranged movably with respect to the first contact and being adapted to make contact with the same in one end position thereof, means for directing a gas blast through the arc formed between the contacts upon separation thereof, an electric circuit connected in parallel to the contacts and including in series connection a resistor and two electrodes separated by an arc gap located outside the path of the gas blast acting on the arc between the contacts, and means arranged downstream relating to the first and second contacts for directing a part of the gas blast to the arc gap separating the electrodes, whereby an arc is started and extinguished, respectively, between the electrodes with a time delay being independent of the main flow of the gas blast.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional elevation of a first embodiment of the present invention;

Fig. 2 is a sectional part elevation of a modification of the embodiment shown in Fig. 1;

Fig. 3 is a sectional elevation of another embodiment of the present invention;

Fig. 4 is a sectional elevation of the upper part of Fig. 3 on an enlarged scale, showing a slight modification of Fig. 3;

Fig. 5 is a partial sectional elevation of another embodiment of the present invention; and

Fig. 6 is a partial sectional elevation of a still further embodiment of the present invention.

2

Referring now to the drawings and first to Figure 1, the circuit breaker has a stationary first contact 1 and a movable second contact 2 which are both designed as hollow tubes and are shown in Figure 1 in the open position thereof. The stationary contact 1 and the lower part of the movable contact 2 are disposed inside an insulating casing 3 provided with means (not shown) for introducing compressed air at the moment when the contact between the contacts 1 and 2 is to be broken. The stationary contact 1 is centered in the casing 3 by means of center pieces such as wings 43. The casing 3 is closed at the top by a metallic body 5 which serves as a guiding member for the movable contact 2 and supports a terminal 31 being in metallic contact with the movable contact 2 through the metallic body 5. A helical spring 4 is arranged between the terminal 31 and a collar 2' of the movable contact 2 and serves for keeping the movable contact 2 in closed position in which it makes contact with the stationary contact 1. The stationary contact 1 is connected through swinging contacts 7 to a tubular contact member 6 serving as the other terminal of the circuit breaker. The contact members 7 are sliding on the tubular contact member 6 which serves as part of a disconnecting switch interrupting the current connection to the circuit breaker.

An electric circuit is connected in parallel to the contacts 1 and 2 and includes in series connection a resistor 8 and two stationary electrodes 9 and 10 separated by an arc gap located outside the path of the gas blast acting on the arc between the contacts 1 and 2. The electrode 9 is arranged inside an insulating casing 11 having an orifice 12 being coaxial with the electrodes 9 and 10. The casing 11 communicates through a conduit 13 with the hollow 14 of the stationary contact 1. The electrode 10 is surrounded by an insulating casing 15 leading the ionized gases from the gap between the electrodes 9 and 10 to a cooling device 16 comprising parallel blades separated from one another by short distances.

The operation of this device is as follows:

In the closed position of the circuit breaker the contacts 1 and 2 are in contact with each other. When it is intended to interrupt the current by means of the circuit breaker, the movable contact 2 is moved away from the stationary contact 1 and an arc is started between the contacts 1 and 2 which is driven by the gas blast set up in the casing 3 into the hollow interior of the contacts 1 and 2 through which the compressed air escapes. The interior of these contacts, and especially the discharge channel 14, is traversed by a blast of highly ionized hot gases coming from the arc. From this blast the conduit 13 which is arranged downstream relatively to the contacts 1 and 2, leads a certain quantity of

ionised gas which forms a current path between the electrodes 9 and 10 so that the auxiliary arc strikes. The resistor 8 is thus branched in parallel to the contacts 1 and 2. When the main arc is extinguished and the pure and insulating compressed air follows the ionised gases in the discharge channel 14, a certain quantity of conducting gas remains in the conduit 13 which has not had time to escape through the orifice 12. The resistor 8, therefore, remains shunted between the contacts 1 and 2 at the moment when the voltage attempts to re-establish itself between the contacts 1 and 2 which are thus well protected against any rapid rise in voltage. It is therefore only with a certain lag that the conducting gases contained in the conduit 13 are discharged and replaced by the pure and insulating compressed air. When the latter in turn escapes through the orifice 12, the conducting path established between the electrodes 10 and 9 by the ionised gases is destroyed, the auxiliary arc is extinguished by the known blast action of the compressed insulating gas and the circuit of the resistor 8 is interrupted. The greater is the volume of the conduit 13 relatively to the section of the aperture 12, the later disappears the conducting path between the electrodes 9 and 10. It is thus possible to regulate at will the duration of insertion of the resistor 8.

In the modification shown in Fig. 2 the blowing blast flow in the casing 11' is taken directly from the casing 3 while the conducting path of thermo-ionic nature is started in the blowing blast flow by the conduit 13' ending at the electrode 9'. The stationary contact 1' and the other electrode 10' have the same operation, respectively, as the stationary contact 1 and the other electrode 10 shown in Fig. 1.

In the case where the switch comprises a rod-like contact associated with a hollow contact, the ionised gas can be taken from a source situated down stream of the hollow contact. Such an arrangement is shown in Fig. 3 where 1'' indicates the stationary hollow contact provided with spark arresters 17, 18, and 2'' indicates the movable rod-like contact. The latter is connected to the resistor 8'' through the intermediary of a sliding contact 19. The ionised gases are collected by means of a collector 20 in which opens the conduit 13'' feeding the electrode 9''. If it is desired to obtain a certain pressure the entry orifice 21 of the collector 20 can be made larger than the outlet orifice 22 of the collector 20. The electrode 9'' is arranged in an insulating casing and opposite to the other electrode 19'' connected to the resistor 8''.

The ionised gas inlet 20 can also be arranged as in the modified construction shown in Fig. 4 comprising a bell-shaped collector 20' open at the bottom and into the interior of which the conduit 13''' penetrates. The latter is closed at its lower part by a plug 23 and a plurality of holes 24 allow the penetration of gas into the conduit 13'''. Holes 25 are provided at the upper part of the bell-shaped collector 20' to allow the circulation of gas into the annular space between the bell-shaped collector 20' and the conduit 13'''. By this arrangement particles from the contacts or the spark arresters are prevented from entering conduit 13'''.

Instead of taking the ionised gas from the flame of the arc it can be taken from fresh air or gas which is subjected to the ionising action of the radiations from the arc. An embodiment of a device of this kind is shown in Fig. 5 in which

the fresh gas is taken from the interior of the casing 3 through a pipe 26 traversing the contact 1^{IV} and led through a tube 27 of material permeable to the ionising radiations (quartz for example) which tube is disposed in the field of the said radiations. This tube communicates with a conduit 13^{IV} connected to one of the electrodes of the auxiliary arc gap (not shown).

If one of the contacts is a rod-like contact, it is also possible to adopt the arrangement shown in Fig. 6 in which 1^V shows a rod-like contact provided with an end point 28 of refractory material (tungsten, carbon or any special composition). In this arrangement it suffices to bore in the contact 1^V a hole 29 opening at the extremity of said contact and to branch on this hole 29 the conduit 13^V feeding the electrode 9^V. The conduit 29 can comprise a closed end 30 serving as trap for metal particles or other impurities. The other parts, such as the insulating casing 11^V provided with the orifice 12^V and the other electrode 10^V connected to the resistor 8^V operate in the same manner as the corresponding parts in the other embodiments.

It is obvious that the invention is applicable to all types of known switches no matter what may be their mode of blowing and independently of the examples given.

It should be understood that any appropriate impedance and particularly a condenser, a condenser shunted by a resistance, an electrolytic or electro-chemical condenser, a resistance varying with voltage, a fuse with automatic regeneration and so on may replace the resistor 8.

Finally, whilst it is not excluded to place the auxiliary arc gap inside the switch, for example inside the discharge passage or at the interior of the casing 3 provided always that the auxiliary arc gap is protected against the direct influence of the main blast flow. It should be understood that the auxiliary arc gap may be placed outside the switch. This last arrangement has the advantage of facilitating the maintenance of the circuit breaker and of allowing a particularly easy control of the operation thereof.

What I claim is:

1. A circuit breaker of the gas blast type, comprising in combination, a first contact; a second contact arranged movably with respect to said first contact and being adapted to make contact with the same in one end position thereof; means for directing a gas blast through the arc formed between said contacts upon separation thereof; an electric circuit connected in parallel to said contacts and including in series connection a resistance and two electrodes separated by an arc gap located outside the path of the gas blast acting on the arc between said contacts; and means for directing a part of the gas blast to the arc gap separating said electrodes, said means including a conduit and an exit orifice of said conduit having a cross-sectional area appreciably smaller than the cross-sectional area of said conduit, whereby an arc is started between said electrodes with a time delay being independent of the main flow of the gas blast.

2. A circuit breaker of the gas blast type, comprising in combination, a first stationary contact; a second contact arranged movably with respect to said first stationary contact and being adapted to make contact with the same in one end position thereof; means for directing a gas blast through the arc formed between said contacts upon separation thereof; an electric circuit connected in parallel to said contacts and including in

series connection a resistance and two stationary electrodes separated by an arc gap located outside the path of the gas blast acting on the arc between said contacts; and means for directing a part of the gas blast to the arc gap separating said stationary electrodes, said means including a conduit and an exit orifice of said conduit having a cross-sectional area appreciably smaller than the cross-sectional area of said conduit, whereby an arc is started between said electrodes with a time delay being independent of the main flow of the gas blast.

3. A circuit breaker of the gas blast type, comprising in combination, a first contact; a second contact arranged movably with respect to said first contact and being adapted to make contact with the same in one end position thereof; means for directing a gas blast through the arc formed between said contacts upon separation thereof; an electric circuit connected in parallel to said contacts and including in series connection a resistance and two electrodes separated by an arc gap located outside the path of the gas blast acting on the arc between said contacts; and means for directing a part of the gas blast to the arc gap separating said electrodes, said means including a conduit, a gas-collecting device arranged at the entry of said conduit and an exit orifice of said conduit having a cross-sectional area appreciably smaller than the cross-sectional area of said conduit, whereby an arc is started between said electrodes with a time delay being independent of the main flow of the gas blast.

4. A circuit breaker of the gas blast type, comprising in combination, a first contact; a second contact arranged movably with respect to said first contact and being adapted to make contact with the same in one position thereof; means for directing a gas blast through the arc formed between said contacts upon separation thereof; an electric circuit connected in parallel to said contacts and including in series connection a resistance and two electrodes separated by an arc gap located outside the path of the gas blast acting on the arc between said contacts; and means for directing a part of the gas blast to the arc gap separating said electrodes; said means including a conduit, a gas-collecting device arranged at the entry of said conduit and having an additional outlet orifice other than the entry opening of said conduit and an exit orifice of said conduit having a cross-sectional area appreciably smaller than the cross-sectional area of said conduit, whereby an arc is started between said electrodes with a time delay being independent of the main flow of the gas blast.

5. A circuit breaker of the gas blast type, comprising in combination, a first contact; a second contact arranged movably with respect to said first contact and being adapted to make contact with the same in one end position thereof; means

for directing a gas blast through the arc formed between said contacts upon separation thereof; an electric circuit connected in parallel to said contacts and including in series connection a resistance and two electrodes separated by an arc gap located outside the path of the gas blast acting on the arc between said contacts; and means for directing a part of the gas blast to the arc gap separating said electrodes, said means including a conduit, a gas-collecting device arranged at the entry of said conduit and an exit orifice of said conduit having a cross-sectional area appreciably smaller than the cross-sectional area of said conduit, said conduit having a sealed end arranged inside said gas-collecting device and holes provided in the conduit wall near said sealed end, whereby an arc is started between said electrodes with a time delay being independent of the main flow of the gas blast.

20 6. A circuit breaker of the gas blast type, comprising in combination, a first contact; a second contact arranged movably with respect to said first contact and being adapted to make contact with the same in one end position thereof; means for directing a gas blast through the arc formed between said contacts upon separation thereof; an electric circuit connected in parallel to said contacts and including in series connection a resistance and two electrodes separated by an arc gap located outside the path of the gas blast acting on the arc between said contacts; and means for directing a part of the gas blast to the arc gap separating said electrodes, said means including a conduit and an exit orifice of said conduit having a cross-sectional area appreciably smaller than the cross-sectional area of said conduit, said conduit including a portion consisting of a material permeable to ionizing radiation and arranged in the path of the radiation of the arc formed between said contacts, whereby an arc is started between said electrodes with a time delay being independent of the main flow of the gas blast.

ANDRÉ LATOUR.
